[57]**CLAIM**

The ornamental design for a combined rodless fluid pressure cylinder and switch installations, as shown and described.

DESCRIPTION

FIG. 1 is a top plan view of a combined rodless fluid pressure cylinder and switch installations showing our new designs;

FIG. 2 is a front elevational view thereof;

FIG. 3 is a bottom plan view thereof;

FIG. 4 is a rear elevational view thereof;

FIG. 5 is a right side elevational view thereof, the left side being identical; and,

FIG. 6 is a front, top, left side perspective view thereof.

FIG. 1

FIG. 2

FIG. 3

FIG. 4

FIG. 5

FIG. 6
